UNITED STATES PATENT OFFICE.

WILLIAM HENRY CHAPMAN, OF PORTLAND, MAINE, ASSIGNOR TO CHAPMAN ELECTRIC NEUTRALIZER COMPANY OF PORTLAND, MAINE, OF PORTLAND, MAINE, A CORPORATION OF MAINE.

DISCHARGE BAR FOR NEUTRALIZING STATIC ELECTRICITY.

Continuation of application Serial No. 127,464, filed August 5, 1926. This application filed April 8, 1927.
Serial No. 181,994.

My invention relates to discharge bars for neutralizing static electricity. More especially it relates to discharge bars or inductors which are placed near the surface of 5 textile fabrics or paper in the process of manufacture or printing, whereby the static charge in these materials is neutralized by the discharge of high voltage alternating charges through the air. This present application is filed as a continuation of application Serial Number 127,464, filed August 10, 1926, and similarly entitled.

An object of the present invention is to provide an improved construction of discharge bar, of the type disclosed in my Letters Patent No. 940,431 of November 16th 15 1909, wherein current is supplied through a cable housed within but insulated from a grounded metallic tube. About this cable 20 are condenser sleeves each of which is connected with a discharge point projecting outside the tube through a longitudinal slot thereof. Certain practical difficulties have been encountered in the use of the use of the 25 bar illustrated in my said patent which it is the purpose of the present invention to eliminate. Among these is the blunting of the discharge points due in part to the wearing action of the emanating ions and in part to 30 the cleaning operations necessary to rid the points of collected dirt or lint in order that their effectiveness may be unimpaired. It has also been found necessary from time to time to remove from the interior of the tube 35 the dirt and lint which enters through the slot; and as such removal requires the disassembling of the bar and subsequent reassembling and installation, time and labor are expended and production lost while the 40 machine on which the bar is placed is idle. In the bar of the aforesaid patent it has also been necessary to guard against the possible slippage of the condenser sleeves along the cable as the latter becomes old and dried 45 and somewhat smaller in diameter. The danger of these sleeves coming into conducting communication with one another is a serious menace where the discharge bar is used in the presence of inflammable vapors 50 such as occur in the manufacture of rubber coated fabrics and the like. Another serious objection to the bar of the patent is the liability of breakage of the protruding ends of

the insulating blocks that encircle the sleeve and house the discharge point. It is, of course, obvious that the bar must be within operating range of the paper or fabric passing by it, but in many machines the space available for the bar is so limited, because of the presence of delivery tapes, fly sticks 60 and other moving parts, that when the bar of the patent is installed the projecting ends of the blocks are necessarily closer than would be desired if more space were available. In consequence these blocks have 65 served to catch upturned edges of paper or other material being neutralized and cause a jam to occur which, before the machine could be stopped, frequently resulted in a splitting of the block beginning usually in 70 the slot engaged by the metallic tube. If one edge of this block is broken away, destroying the slot formation on its side and freeing it from the tube, the discharge point may be brought near enough to the tube to 75 permit the current to jump thereto by spark discharge, or the block may tilt and rest against the inside of the tube resulting in a loss of the charge by leakage through this 80 surface contact.

It is an object of the present invention to provide an improved insulating block for the condenser sleeves and the discharge points which will act as positive spacers to prevent the sleeves from coming into contact with one another and which will also serve collectively to close the slot opening in the outside tube. It is a feature that the insulation blocks are so shaped that they are properly supported by limited contact with 85 the inside surface of the tube, serve to support the cable centrally therein, and project just into the slot of the tube without projecting beyond it. Another object is to provide discharge points which are not affected 90 either by such cleaning as is necessary or by the discharging ions.

These objects and the features which characterize the improved construction herein disclosed are attained by providing an insulating block having bearing surfaces of limited extent adapted to rest against the inner surface of the cylindrical tube to retain the block in position. The bottom portion of the block projects into a longitudinal slot of 105 the tube, and is of such width that when the

tube is filled with the blocks and the bottom portions are in end contact with one another, they completely fill the slot and prevent entrance of dirt or lint to the tube. A hole in the body of the block receives the metallic sleeve which serves as the condenser. This body portion is shorter than the bottom portion and the condenser sleeve is just long enough to extend through this body portion and be headed over on both ends. Consequently when the longer bottom portions are in contact the shorter body portions are spaced apart and thus the condenser sleeves are positively prevented from coming into conducting communication.

The discharge points are provided by inserting in each condenser block a U-shaped wire with its inverted base in contact with the condenser sleeve and with its depending legs extending through suitable openings provided in the bottom portion of the block. By choosing a wire of sufficiently small diameter, it is immaterial as regards its effectiveness as a discharge point, whether its end is sharpened or not. Consequently the ends are preferably left unsharpened, and it follows that thereafter the cleaning of the ends or the wearing action due to the discharge does not injuriously affect the points. The legs of the U-shaped wire near this base are crinkled to engage the sides of the hole through which the legs extend so that the points will be maintained centrally thereof.

It is intended that the patent shall cover by suitable expression in the appended claims, whatever features of patentable novelty exist in the invention disclosed. In the accompanying drawings:

Figure 1 is an elevation of a discharge bar embodying the present invention, showing its relation to the material being neutralized, and with its electrical connections illustrated somewhat diagrammatically;

Figure 2 is a plan of the discharge bar with a portion of the tube cut away to show the insulating blocks;

Figure 3 is an elevation in section on line 3—3 of Figure 2, but with some of the condenser blocks in full view; and

Figure 4 is an elevation somewhat enlarged, of a section taken transversely of the bar as on line 4—4 of Figure 3.

Referring to the drawings, the improved discharge bar comprises a metallic tube 10, which fits upon an insulating terminal block 12 and is held thereto by a strap 14 and screws 16. A cable 18, having a heavy insulated covering 18', is secured within a socket 12' in the terminal block 12, by a metallic block 20 to which the wire 18" is preferably soldered. A pin 22, which threads into the cable block 20 and contacts with the wire 18, is clamped to the terminal block 12 by binding nut 24 and is adapted to be connected with a lead 26 from a source

of high tension alternating current. The cable 18 extends through the hollow of the tube 10 into a socket provided in an insulating plug 28 which closes the end of the tube.

Intermediate the terminal block 12 and the plug 28 are several condensers in the form of metallic sleeves 30 slidably fitting about the insulating covering 18'. Preferably these sleeves are made of aluminum because of its ability to resist corrosion but other suitable metals could be employed if desired. Each sleeve extends through a cylindrical hole in the body portion 32^a of an insulating block 32. These blocks can be made of any insulating material although I prefer to use porcelain because most other moulded insulating material is subject to carbonization. Each block has a bottom portion 32^b which is somewhat narrower than the main or body portion 32^a through which the sleeve 30 extends, although longer in extent so that the ends of the bottom portions lie outside and beyond the headed ends of the sleeve. This results in the sleeves being maintained in separated relation when their blocks are placed adjacent to one another endwise. Sections 32^c at both ends of the blocks extend upwards and downward from the main body portion to form bearing surfaces 32^d of limited extent which rest against the inside surface of the tube, there being thus four such bearing surfaces at each end of the block. It is important that the surfaces of the blocks in contact with the tube wall be limited in extent as otherwise, with too large a surface contact, the charge will be dissipated through the block to the tube and thus render the bar ineffective as a neutralizer. On the upper side of the block, between the extended sections 32^c, a slot opening 32^e to the sleeve hole is provided and opposite this slot on the underside of the hole wall is a corresponding groove 32^f connecting two smaller holes 32^g extending downward through the bottom portion 32^b. Before the sleeve is placed in the main hole, a U-shaped wire 34 is passed through the upper slot and main hole until its base 34^a rests in the groove 32^f and its depending legs 34^b extend through the smaller holes 32^g. Each leg is crinkled near its junction with the base portion and these crinkles 34^c are so proportioned with respect to the size of the holes that when the leg is passed through, the turns of the crinkles engage the hole and centralize the depending straight part of the leg in the hole opening. Preferably the latter is countersunk to make a flaring opening 32^g as seen clearly in Figure 4. The wire 34 is slightly thicker than the depth of the groove 32^f so that when the metallic sleeve 30 is passed through the main hole, it will make good contact with the base of the U-shaped wire.

I have found by practical experience that

a wire as fine as .016 inch diameter, or finer, and of a length as much as thirty times its diameter is just as efficient a discharger whether it is sharpened at the end or not.

5 The discharge points of my new bar are constructed to meet this naturally imposed condition and an advantage is thereby secured over the construction shown in Patent No. 940,431 in which long experience has

10 shown that the blunting of the discharge points by usage or any accumulation of lint or dirt about the points causes a serious drop of efficiency. Points of that shape must remain sharp to be effective, but the

15 action of the discharge current as well as the operation of cleaning the points has a constant tendency to blunt them, whereas the points in my present discharge bar do not become changed in their effective condition

20 by any amount of wear to which their ends may be subjected either by the wearing action of the discharge current or of cleaning because the cross section of the metal constituting the point is uniform throughout its

25 length and small enough to be effective at whatever length it is likely to be reduced by wear.

There is a longitudinal slot 10^a on the underside of the tube 10 which is just wide enough to accommodate the bottom portions 32^b of the blocks. Accordingly when the sleeves and blocks are inserted in the plug end of the tube (prior to the plug being fastened thereto) and the cable is passed

35 through the sleeve, the bottom portions slide along the tube slot with the bearing surfaces 32^d of the blocks resting on the tube's inner wall. It is intended that a sufficient number of such blocks will be inserted in the

40 tube so that when placed in end contact their bottom portions will completely fill the slot 10^a in the tube. If for any reason this does not result, short pieces 36 of fibre tubing may be fitted into one or both ends of the

45 tube to hold the blocks in contact and cover any part of the slot opening not filled by the bottom portions of the block. It is not necessary that the portions 32^b extend outside of the tube 10 in fact, where the space in which

50 the bar is positioned is restricted, it is desirable to have the portions 32^b just flush with the outside surface of the tube 10 as shown in the drawings.

In operation my improved discharge bar

55 is located with its active points 34^b near to the surface of the paper or fabric 38 to be treated. Connection is made from a source of high voltage alternating current of about 10,000 volts through the lead 26 and bayonet

60 socket 26' to the terminal pin 22. The high voltage charge is thus communicated to the cable 18. The wire 18" in this cable constitutes the inside electrode of a condenser, the covering 18' of the cable is the

65 dielectric and each one of the aluminum

sleeves 30 is an outside electrode of the condenser and has an alternating charge induced in it of a voltage practically the same as that in the cable, but of such a very limited quantity that its discharge will not set fire to the most inflammable vapors, although of sufficient quantity to neutralize all the charge that can exist on any amount of paper or fabric that can be made to pass before a single pair of the discharge points 34^b.

The induced alternating current in the condenser sleeves 30 flows through the wires 34 and is discharged into the air from their points 34^b. If the paper is negatively charged, as is usual, the positive ions, represented by the small arrows in Figure 1, will pass to the paper and neutralize the negative ions thereof, and the negative ions will flow to the tube 10 which must be grounded as indicated at 40. Upon the paper becoming neutralized both positive and negative ions flow to the tube and are dissipated through the ground connection.

The blocks 32 because of their bearing surfaces on the tube hold the cable centrally of the tube 10 and prevent sagging thereof. The bottom portions fill the tube slot and keep out dirt and lint from the interior of the tube and serve also, by engaging the walls of the slot, to prevent the blocks from rotating. Moreover, these portions, because they are longer than the body portions of the body, prevent the condenser sleeves from coming into contact or close enough to cause sparks. This is very important where the bar is used in the presence of inflammable vapors. And since the bottoms 32^b are merely flush with the tube there is no danger of the paper or other material passing the bar being caught by them and forming a pile of the material with consequent strain on the block. With this danger avoided, the bar can be placed in a more restricted space than have the bars heretofore used and still function properly without interfering with the passage of the material.

I claim as my invention:

1. A discharge bar for neutralizing static electricity comprising, in combination, a grounded metallic tube having a longitudinal slot along one side; insulating terminal blocks closing its ends; an insulated cable within said tube extending between said terminal blocks; a series of insulating blocks arranged within said tube about said cable having bearing surfaces of limited extent adapted to rest on the inner wall of said tube and having bottom portions extending into the tube slot; condenser sleeves carried by said blocks in separated relation to one another about the cable; and a discharge wire for each sleeve having connection therewith and having a discharge point extending through said bottom portion of the

block; the said bottom portions being adapted collectively to fill said tube slot when placed in end to end contact.

2. A discharge bar for neutralizing static electricity comprising, in combination, a grounded metallic tube having a longitudinal slot along one side; insulating terminal blocks closing its ends; an insulated cable within said tube extending between said terminal blocks; a series of condenser sleeves about said cable; a series of insulating blocks arranged within said tube, each having a body portion rigidly encasing a condenser sleeve and having its ends extending transversely beyond the body portion to form corner supporting surfaces of limited extent for contact with the inside surface of the tube, and having a bottom portion extending into said tube slot; and a discharge wire in each block having connection with said sleeve and having discharge points extending through said bottom portions; the said bottom portions of said blocks being longer than said body portion whereby the said sleeves are restrained from conducting communication when said blocks are in end contact along said tube.
3. A discharge bar for neutralizing static electricity comprising, in combination, a grounded metallic tube having a longitudinal slot along one side; an insulated cable extending along the axis of said tube; an insulating block having at its ends laterally extended portions forming bearing surfaces of limited extent adapted to slide along the inside of said tube, having a lon-

gitudinal hole bushed with metal surrounding the said cable, and having two lateral openings on the side presented to the tube slot; and a discharge wire having its middle portion in contact with said metal bushing and its two end portions crinkled to hold them in central position in the two lateral openings through which they emerge to outside the surface of the insulating block.

4. A discharge bar for neutralizing static electricity comprising, in combination, a grounded metallic tube having a longitudinal slot along one side thereof; insulating terminal plugs closing its ends; an insulated cable within said tube extending between said terminal plugs; a series of condenser sleeves encircling said cable at spaced intervals therealong; a supporting block of insulated material for each said sleeve having its body portion around the sleeve and having its ends laterally projecting to form bearing surfaces of limited extent for contact with the inner wall of said tube for supporting said sleeve and cable centrally therein; each said block having a portion along one side thereof of greater longitudinal extent than said body portion and extending into said tube slot, whereby the said slot is closed by said side portions when placed end to end and whereby the sleeves are maintained in spaced relation to one another; and conducting means leading from said sleeves through said projecting side portions.

WILLIAM HENRY CHAPMAN
